UNITED STATES PATENT OFFICE.

JOSEPH EVANS COOPER, OF CHICAGO, ILLINOIS.

BREATH DEFLECTOR OR GUARD.

1,077,042.

Specification of Letters Patent.

Patented Oct. 28, 1913.

Application filed December 23, 1912. Serial No. 738,292.

To all whom it may concern:

Be it known that I, JOSEPH E. COOPER, a citizen of the United States, residing at Chicago, in the county of Cook and State of Illinois, have invented certain new and useful Improvements in Breath Deflectors or Guards; and I do declare the following to be a full, clear, and exact description of the invention, such as will enable others skilled 10 in the art to which it appertains to make and use the same.

This invention relates to a sanitary breath deflector or guard especially designed for use by barbers and dentists for use on themselves and customers.

One object of the invention is to provide a simply constructed and efficient device for preventing the breath of the user from issuing straight forward and to cause it to be 20 discharged to one side or toward the rear and thus prevent its coming in contact with a person in front of the user.

With this and other objects in view, the invention consists of certain novel features 25 of construction, and the combination and arrangement of parts as will be more fully described and claimed.

In the accompanying drawings: Figure 1 represents a top plan view of this improved 30 guard; Fig. 2 represents a rear elevation thereof; Fig. 3 is a detail longitudinal section taken on the line 3—3 of Fig. 2; Fig. 4 is a detail perspective view of the reinforcing member for the nose opening; Fig. 5 is a 35 similar view of one of the clamping levers.

Very often the breath of barbers, dentists and the like is objectionable to the patient or customer and vice versa and often times is unsanitary and causes infection should 40 the operator or the patient be affected with catarrh, tuberculosis or some other infectious disease, and it is to avoid this unpleasantness and danger that this device is designed.

45 In the embodiment illustrated the breath deflecting casing 1 is shown composed of rubber or any suitable material, said casing being substantially arc shaped and preferably tapering toward its ends to adapt it to 50 occupy as small a space as possible. As shown this casing 1 is composed of two tubular members tapering toward one end and with their large ends arranged adjacent to each other and connected to form 55 the arc shaped casing. The adjacent large ends of these tubes are cut out to form a

nose opening 2 which is designed to fit over the nostrils of the wearer and is reinforced on its edge by any suitable means, a loop shaped longitudinally curved wire 3 being here shown housed in a casing surrounding said opening formed by the cut out portions of the adjacent tubes. The sides of the tube opposite the openings or cut out portions are curved inwardly and 60 provided with pockets to be described.

A cross bar 4 connects the side members of the loop 3 and has an out-struck loop 5 to receive a spring 6 the use of which will be hereinafter described. This bar 4 also has bearings 7 on its side edges in which are pivotally mounted gripping or guard retaining levers 8. These levers are constructed as shown in Figs. 3 and 5 with flat nose gripping fingers or plates 9 offset inwardly from the body portions thereof and designed to be housed in the pockets 11 which project laterally into the casing opposite the opening 2 therein. The body portions of these levers project forwardly and 75 are provided at their outer ends with operating elements or handles 10 herein shown in the form of disks which are designed to be pressed toward each other against the tension of the spring 6 which bears against 80 the opposed faces of said levers, for forcing the clamping or gripping plates 9 outward to permit the partition between the nostrils to pass between said plates 9. When the handles 10 are released the spring 6 forces 85 the outer ends of the levers apart, thus forcing their inner clamping ends 9 toward each other into gripping engagement with the nose partition thereby reliably holding the device in operative position. The spring 90 6 is preferably U-shaped as shown clearly in Fig. 3, but any other form of spring may be employed.

The bar 4 extends transversely of the casing 1 on the outer face thereof opposite the 100 opening 2 therein and forms a connection between the tubes forming the casing and also serves to close said tubes at this point to prevent the breath of the user from passing out between the ends of the tubes. The 105 wire loop 3 which is inserted within a casing around the opening 2 forms a reinforce for said opening to hold it in proper position against the nose of the wearer, the upwardly curved portion 3' thereof being designed to fit closely against the lip below 110 the nose.

The pockets 11 may be constructed in any suitable manner and are shown composed of the ends of the tubes folded back and secured by any suitable means and which are designed to form cushioning means for the 5 clamping plates or fingers 9 of the levers 8 and thereby prevent injury to the partition of the nose with which they are engaged.

10 In the application of this device the parts being in the position shown in Figs. 1 and 2, the handles 10 are engaged between the fingers of the user and pressed toward each other thereby forcing the pockets 11 containing the clamping fingers 9 apart a sufficient distance to permit them to be inserted in the nostrils of the wearer on opposite sides of the nose partition and when the handles are released they firmly grip said 15 partition and hold the device in operative position over the nose of the user. The open ends of the casing are directed by the peculiar curvature thereof toward the rear of the head and so discharge the breath in 20 that direction.

25 While I have described my invention with more or less minuteness as regards details and as being embodied in certain precise forms, I do not desire to be limited thereto unduly any more than is pointed out in the 30 claims. On the contrary, I contemplate all proper changes in form, construction and arrangement, the omission of immaterial elements and substitution of equivalents as circumstances may suggest or render expedient.

I claim as my invention:

1. A breath guard comprising a tubular casing having an opening in one side wall thereof, clamping levers fulcrumed in the

40 wall of said casing opposite said opening with their gripping ends projecting into the casing, and resilient means mounted outside said casing for forcing the clamping ends of the levers normally toward each other.

45 2. A breath guard comprising a tubular casing having an opening therein intermediate of its ends, longitudinally spaced levers fulcrumed on said casing with their inner ends offset inwardly to position them in close relation, said ends extending laterally into said casing from its inner face, the other ends of said levers being arranged outside said casing, and a spring arranged between said levers outside the casing for 50 forcing their outer ends apart and their inner ends toward each other.

55 3. A breath guard comprising a tubular casing having an opening in one side wall intermediately of its ends, said opening extending substantially the entire width of said casing, a longitudinally curved wire loop arranged around the edge of said opening, a cross bar connected with the side members of said loop outside said casing, 60 nose engaging levers fulcrumed on said bar and having one end extending into the casing, said inner ends being bent toward each other, and yieldable means for holding said 65 ends in close relation.

70 In testimony whereof I have hereunto set my hand in presence of two subscribing witnesses.

JOSEPH EVANS COOPER.
